UNITED STATES PATENT OFFICE.

EMIL ANDERSON, OF YONKERS, NEW YORK, ASSIGNOR TO THE UNIVERSAL TURBINE COMPANY, OF NEWARK, NEW JERSEY, A CORPORATION OF NEW JERSEY.

TURBINE.

1,243,477.

Specification of Letters Patent. Patented Oct. 16, 1917.

Application filed February 9, 1915, Serial No. 7,098. Renewed March 8, 1917. Serial No. 153,461.

To all whom it may concern:

Be it known that I, EMIL ANDERSON, a citizen of the United States of America, and a resident of Yonkers, county of Westchester, and State of New York, have invented certain new and useful Improvements in Turbine-Engines, of which the following is a specification, reference being had to the accompanying drawings, forming a part thereof.

My invention relates to turbine engines and has special reference to such as are driven by an expansible motive fluid such as steam.

15 This invention pertains to engines of the same general character as that set forth and described in my copending application, Serial No. 724,516, filed October 8, 1912, and patented Dec. 19, 1916, No. 1,208,888, and 20 has for one of its objects to provide an improved engine of this kind which is capable of developing its power efficiently.

Other objects and advantages of my invention will be set forth hereinafter and in 25 order that my invention may be thoroughly understood I will now describe the same in the following specification and then point out the novel features thereof in appended claims.

30 Referring to the drawings:

Figure 1 is a sectional side elevation of an engine which embodies my invention.

Fig. 2 is a detail view of a portion of the 35 rotor of the same machine drawn to a larger scale.

A transverse sectional elevation of the rotor is shown in Fig. 3.

Fig. 4 is a sectional elevation of a portion 40 of a slightly modified engine structure which also embodies my invention.

Corresponding parts are designated by the same reference characters in all of the figures.

The engine of Figs. 1, 2 and 3 comprises 45 an annular frame 10 forming a part of the stator of the machine, nozzle sections 11, only one of which is shown in detail, and a rotor structure 12.

The nozzle 11 comprises a hollow sector 50 having an inlet opening 13 and a plurality of inclined discharge openings 14, which are formed by vanes or spacers 15.

The rotor structure 12 comprises a disk or plate 16 to which is secured a rotor 17. This rotor is composed of a pair of annular plates 55 18 which are spaced apart by multi-section curved bucket spacers 19. Each of these spacers, as clearly shown in Fig. 2, has a relatively short radius bend at 20 near the discharge end of the rotor.

60 Between the spacer sections are a plurality of wavy disks 21 which are substantially parallel to the annular plates 18. The spacers and disks are riveted together and to the annular plates although some other 65 means may be employed for making them into a unitary structure.

While the disks 21 are corrugated transversely to form wavy passages between them as in my co-pending application to which 70 reference has already been made, they differ from the disks in my previous invention by reason of the fact that they are notched or cut back to leave the space adjacent to the short radius bends of the buckets unob- 75 structed and undivided.

The structure of Fig. 4 is similar to that of the previous figures, except that small auxiliary buckets 22 are provided between the buckets 19.

80 The operation of the machine will be understood from the description of the device, steam being admitted through the intake opening 13 into the hollow chambers of the nozzle sectors, is then discharged through 85 the outlet openings 14 and passes through the passages which are transversely wavy near their intake ends and are curved backwardly near their outer ends.

The steam is compelled to do work upon 90 the rotor in going through the wavy portion of the passage and produces the desired rotation. The short radius bend of the buckets turns the steam backwardly and takes up the remainder of the force of the steam due 95 to its velocity.

The corrugated disks are cut away adjacent to the bend in the buckets in order that the entire force may be applied to the bucket with a view to increasing the efficiency of the machine.

100 The engine is effectively operative with but a single nozzle, but a plurality of nozzle sections will usually be employed.

Structural modifications may be effected within the spirit and scope of my invention, and I intend that only such limitations be imposed as are indicated in the appended 5 claims.

What I claim is:

1. A turbine rotor comprising a pair of spaced annular plates, interposed buckets each having a relatively short radius bend 10 near its discharge end and means for providing transversely wavy passages between the buckets adjacent to the intake end.
2. A turbine rotor comprising a pair of spaced annular plates, interposed bucket 15 spacers, each having a relatively short radius bend near its discharge end and substantially parallel wavy vanes interposed between the bucket spacers near their intake

end and cut away adjacent to the short radius bend of the bucket spacers.

3. A turbine engine comprising a rotor having a plurality of buckets and means for providing a plurality of transverse fluid passages between the buckets adapted to produce a plurality of parallel wavy paths 25 adjacent to the intake end of the buckets and means for passing motive fluid through said buckets.

In testimony whereof I have hereunto set my hand this 1st day of February, 1915, in 30 the presence of two subscribing witnesses.

EMIL ANDERSON.
